UNITED STATES PATENT OFFICE.

EDWIN R. CAHOONE AND NOBLE TEAS, OF NEWARK, NEW JERSEY,
ASSIGNORS TO SAID CAHOONE.

COACH OR HARNESS PAD.

SPECIFICATION forming part of Letters Patent No. 223,991, dated February 3, 1880.

Application filed October 13, 1879.

To all whom it may concern:

Be it known that we, EDWIN R. CAHOONE and NOBLE TEAS, both of Newark, in the county of Essex and State of New Jersey, have 5 invented a new and useful Improvement in Coach or Harness Pads, of which the following specification is a description.

The object of our invention is to produce a pad for team-harness for farmers and others 10 adapted for the back of any and every horse, whether fat or lean.

Our invention therefore relates to that kind 15 of pad which has a yielding center, being stiff on the sides to keep the stuffing in its proper place and give a handsome appearance to the article.

In the accompanying drawings, Figure I represents the top of one side of the pad, complete in all its parts, ready to receive the 20 straps which fasten it to the harness, the other side being the same. Fig. II is a cross-section of the pad cut lengthwise on a line, *x x*, of Fig. I, through the center. Fig. III is a view of the under side of the under plate, showing 25 the holes for the pad-screws, burrs, and holes for the inserting of the burrs for the terrets, &c. Fig. IV is a top view of one side of the pad-plate, without the end pieces or any other part of the pad, showing the parts for fastening 30 the upper and lower lock-pieces. Fig. V is a view of the leather piece which forms the top or finish of the pad. Fig. VI is an under view of the lower lock-piece for holding the loop L. Fig. VII is a top view of the upper 35 lock-piece for holding the center leather piece which covers the spring and unites the two frames together. Fig. VIII is a view of the D, which, when locked into its place, receives the straps for fastening to the harness. 40 Fig. IX is a view of the steel spring detached. Fig. X is a view of a pad-hook cut in two lengthwise to show the depression for the spring. Fig. XI is a view of a section cut crosswise through the lock-piece I, showing 45 the rivets that secure the spring and the different parts together.

Similar letters of reference indicate corresponding parts in all the figures.

In this style of pad a degree of firmness is 50 required not attainable with leather, as the

plates are in separate pieces and bend at the center; hence we employ a steel spring beneath the leather at the center of the pad, riveted to the cast-metal plate and forming one continuous plate.

The pad-hook is made with a depression on its under side to receive the spring, as seen in Fig. X, so as to set smooth with the hook as if it formed a part, helping to keep the parts in their places.

We also find it necessary to make openings P in the plates D, to receive the burrs z for the upper or center pad-screw, this being essential to make the pad complete for changing trimmings.

Devices for changing trimmings are old; but an upper burr-hole was never needed before, but becomes a necessity in this style of pad.

In making this invention we make distinct 70 locks differing each from the other, one kind at the outer ends and the other kind at the middle or center of the pads. The object of these locks is, first, the lower ones secure the loop L and the upper ones secure the parts 75 uniting the two sides together, while the pad-screws n serve as keys to lock and unlock the parts at the same time.

We have made the middle parts of the pad-plates E exactly parallel with the binding 80 edges i, sufficiently below the top of the binding-edges to admit of the thickness of the top leather, H, this being essential in this construction to make a good job.

Having thus described our invention, what 85 we claim, and desire to secure by Letters Patent, is—

1. In a coach or harness pad with a spring center, the combination of the leather H and plates E for such pads, made with elevated 90 flanges or binding edges, to receive the leather within their sides and upper edges, substantially as specified.

2. A coach or harness pad with a spring center, having ribs F at the top or center ends 95 of the plates to receive the lock-piece J, having jogs j, and having at their lower ends curled or turned-down portions to receive the curled-down portion m on the lower lock-piece, I, all combined substantially as specified.

3. A harness-pad having two side plates and a connecting-spring, in combination with compound end locking-pieces, substantially as described.
5. 4. A center iron, D, in the pad part, constructed as shown, for changing trimmings, having an opening, P, near the center, to receive the burr for changing the pad-screws which are used to lock the middle portion of the pads, substantially as herein shown and described.
5. The pad-hook R, in combination with the spring K and the middle or center leather piece, j', substantially as herein shown and described.

EDWIN R. CAHOONE.
NOBLE TEAS.
